CLAIM

The ornamental design for a ceiling fan motor housing, as shown and described.

DESCRIPTION

FIG. 1 is a top perspective view of a ceiling fan motor housing in the environment of the ceiling fan, showing my new design;

FIG. 2 is a bottom perspective view thereof, having the ceiling fan environment removed;

FIG. 3 is a bottom view thereof;

FIG. 4 is a top view thereof; and,

FIG. 5 is a side view thereof.

The broken lines illustrate portions of the ceiling fan motor housing and ceiling fan environment. None of the broken lines form part of the claimed design.
